UNITED STATES PATENT OFFICE.

ALEXANDER HAIDIN, OF GARY, INDIANA.

TELESCOPIC AIRSHIP.

1,002,682.

Specification of Letters Patent.

Patented Sept. 5, 1911.

Application filed October 24, 1910. Serial No. 588,795.

To all whom it may concern:

Be it known that I, ALEXANDER HAIDIN, a citizen of the United States, residing at Gary, in the county of Lake and State of Indiana, have invented certain new and useful Improvements in Telescopic Airships, of which the following is a specification.

My invention relates to improvements in telescopic air ships and particularly to ships of the dirigible balloon class for navigation of the air.

One of the objects of my invention is to provide a ship, of the class referred to, wherein the gas holding portion is divisible into a plurality of separable, independent gas-holding receptacles.

Another object is to provide, in a ship of this character, a centrally located passenger compartment, and below the passenger compartment 20 a machinery compartment from which each gas-holding receptacle may be controlled; the propelling power regulated; and the course of the craft directed.

Another object of my invention is to provide means whereby the buoyant hydrogen gas may be introduced into any one or all 25 of the receptacles from the central compartment.

Another object is to provide separate 30 means for propelling the craft while in water, and being used as a marine vessel, from that used to propel it while in the air.

Another object is to provide a steering 35 means that may be employed for directing the course of the ship whether it be operating as an aerial or a marine craft.

Other and further objects of my invention 40 will become readily apparent to persons skilled in the art from a consideration of the specification taken in conjunction with the drawings, wherein—

Figure 1 is a central longitudinal section of the ship; Fig. 2 is an enlarged fragmentary view showing one of the separable gas receptacles; Fig. 3 is a transverse section of the same showing one of the bulk heads, man hole, and connecting rings.

In all of the views, the same reference 45 characters indicate similar parts.

My ship consists generally of two major 50 parts, 5, the hull of a marine vessel, preferably made of aluminium or other light buoyant metal, in which the gasometer, 6, composed of a number of separable gas retaining and holding receptacles, is to be

placed and secured. The general relation of these parts is such that the gasometer, preferably tapered at each end to a point, has its lower side and ends surrounded by the similarly shaped hull within which it is contained, so that both pointed ends of the gasometer are protected by the strong hull structure. Thus, when the vessel is in water, the gasometer lies partly below water lever. This arrangement makes for compactness and efficiency of a ship used for aerial and marine navigation. In the center of the craft, the receptacle is divided vertically by means of the partition or floor, 7, above which is the top compartment, 8, and below which is a machinery compartment 9, provided with an engine, 10, for furnishing the propelling power.

11 is a pump for pumping gas into the various compartments through the pipes 12 and 13. Similar pipes 14 and 15 communicate with the receptacles and with the chimney 16, for the purpose of permitting the escape of gas from any one of the individual compartments. On the right hand side of the central chambers 8 and 9 are gas receptacles, 17, 18, 19, 20, 21, and 22. On the left hand side of central chambers 8 and 9 are the receptacles 23, 24, 25, 26, 27, and 28, which are substantial duplicates of the respective compartments on the right hand side. Valves permitting gas to be introduced into the respective receptacles are indicated by the same reference characters that indicate the respective receptacles, with the exponent "a," and the rods for controlling the valves pass through the respective receptacles and terminate in the engineer's compartment 9, and are indicated by the same reference characters as that indicating the respective receptacles with the exponent "b." The arrangement is such that any one of the valves *a* may be controlled from the engineer's room independently of any other valve by means of the respective rods *b* through or by which the valve is operated.

It will be observed that the propeller 30 connected at the rear end of the ship is driven by the train of gears, 31', connected to a shaft 30', through the train of gears, connected to the engine 10. This shaft 30' may pass through the various gas holding receptacles, as shown, and be properly packed to prevent leak, or it may be passed

on the outside of the device as may be desired, or other means than that shown may be employed for rotating the propeller 30.

Secured to the hull 5, at each end, is a frame, 31—31^a, supporting a stationary axle or frame 32. A similar bar 33, 33^a, has a swivel connection 34—34^a with the bar 33. Wheels 35 have rotary bearings on the bar 33, and are rotated. They are located immediately under the central median line of the airship. The wheels 35 are provided with webs 36 on the opposite side of which are spokes 37, to provide strength for the webs. The spokes, 37, extend from the hub, 38, to the rim, 39, to give strength to the structure. A web or disk 36 acts as a rudder for the ship whether it is in the air or in the water. A rod 40 is pivotally connected to each of the wheels, as at 41. A rod 42 extends vertically to a point 43, where the pilot is located in the rear of the guard windows, 44. The fore and aft movement of the rod 42 will deflect the wheels 35 and 35^a in such manner as to change the direction of travel of the ship just as the deflection of the rudder of an ordinary ship will change the direction of its course.

Chains, 45—45^a, extend from the engine 10 preferably upon the outside of the shaft, 30 and are connected to the wheels 35—35^a by means of sprocket wheels, 46, so that when the craft is in the water these wheels 45 may be rotated and serve to propel the ship by means of the spokes or blades, 37. A pair of 35 wheels, 48, similar to the wheels 45 only somewhat larger are provided with blades, 49, only, as they are without the dividing web or disk 36 of the small wheels. They are connected to the crank shaft 50 of the 40 engine, by any suitable means whereby they may be readily disconnected and connected when they are required for the propulsion of the ship.

Referring now to Figs. 2 and 3, each receptacle is provided with a bulk head, 51, having a flange, 52, with inside screw-threads, the other end of the receptacle being provided with a coating internally threaded ring, 53. Between the ring and the 50 flange is a packing ring 54 to produce a gas-tight joint. The bulk head at one end of the receptacle is connected to the ring, 53, at the other end of the receptacle by suitable walls, 55, which may be made of aluminium, properly prepared canvas, or other light material. Should canvas be used, a skeleton frame, connecting the two connecting rings of each receptacle may be used to support the canvas but for sake of clearness of illustration, 55 I have not included it in the drawings. The bulk head is provided with a man hole, 56, plates or covers, 57, and a crab, 58. The plate is held in position against the surface of the man hole to provide a gas-tight joint by means of the bolt, 59, and the nut, 60, as

usual in such structures. In the construction of my machines, the several receptacles are screwed together, and made substantially gas tight. The several pipes and rods are then passed through the receptacle, and are packed in the proper manner to prevent the leak of gas from one receptacle to the other. If desired, the entire number of rods may be passed through a single tube or other means than that shown may be employed for controlling the valve of the several receptacles from a central point. After the device has been put together in the proper form it is ready to be inflated.

Hydrogen gas, for the purpose of inflating the several receptacles, may be made by any approved or convenient method in the central compartment, and pumped into the several receptacles through the pipes 12 and 13, from the central lower compartment by means of the pump 11, or, instead of making the gas, a suitable receptacle carrying the hydrogen gas may be stored in the lower compartment, and by means of any variable pressure valve it may be let out into the pipes 12 and 13, and thereby passed to the respective receptacles, that are controlled by the respective inlet valves from the central compartment. In this event, the pump will not necessarily be required. The method of procuring the gas is not a part of my invention. I do not, therefore, deem it necessary to describe specially any method of making it.

When it is desired to start the craft from the ground for an aerial trip, the wheels, 48, are preferably rotated, and the propeller 30 is similarly rotated for the purpose of giving the craft a forward movement upon the ground, if the receptacles have not been sufficiently filled with gas to give the sufficient buoyancy of the craft to lift the ship from the ground and sustain it against the effect of gravity. The propeller 30 is the means by which it is propelled when in the air. The course of lateral direction may be readily changed by manipulation of the wheels 35 upon their respective bearings, just as it would be changed if an ordinary rudder were employed for the purpose; its altitude may be varied by controlling the valves of the receptacles to permit escape of gas or to admit more gas.

Should the ship be placed upon the surface of the water, the motor power connected to the propeller 30 should be disconnected and connected to the wheels 48 and 35, which are adapted to be rotated at a much slower relative speed than the propeller 30. By this means, the vessel will be propelled through the water and may be deflected from a straight course by means of the rudder wheels 35, just as they govern its course when in the air.

While I have herein described a single

embodiment of my invention for the purpose of proper disclosure, it is apparent to those skilled in the art that many changes may be made within the scope of the claims, 5 without departing from the spirit of my invention.

What I claim is:

1. In a ship of the character described, the combination with the source of power 10 and air and water propelling means, of a gasometer providing a central portion of relatively large diameter and end portions tapering from the central portion to a point, said gasometer adapted to raise said ship in 15 air, and a ship hull of shape similar to that of the gasometer to surround the lower side and pointed ends of the latter, said hull giving support to said source of power and propelling means.
2. In an air ship, a gas holding structure 20 divisible into a plurality of gas receptacles, each said receptacle having a bulk head provided with a man hole and man-hole closure, and an internally screw-threaded flange 25 at one end, and an externally screw-threaded ring on the other end.
3. In a ship of the character described, the combination of a long narrow gasometer 30 having tapering ends, a similarly shaped protecting hull adapted to support the ship in water and surrounding the lower side and pointed ends of said gasometer in contact

with the surface thereof, a source of power, and driving means for propelling said ship in air and water respectively having independent connections with said source of power. 35

4. In a ship of the character described, a central structure providing a passenger compartment, gas receptacles of gradually varying diameter extending forwardly and backwardly therefrom, and connections between adjacent receptacles comprising a part upon the larger telescoping over a part upon the 40 smaller receptacle. 45

5. In a ship of the character described, the combination of a gasometer comprising a series of independent receptacles of gradually varying diameter, each formed of a bulk head having a screw-threaded portion, 50 a ring having screw-threads for co-action with the bulk head of the adjacent receptacle, and a gas tight covering; and a hull of shape corresponding with that of the gasometer whereby said ship hull affords protection for the gasometer, driving means, 55 and a source of power supported by said hull.

In testimony whereof I hereunto set my hand in the presence of two witnesses.

ALEXANDER HAIDIN.

In the presence of—

MARY F. ALLEN,
W. LINN ALLEN.
